UNITED STATES PATENT OFFICE.

JOHN ZANDER, OF CHICAGO, ILLINOIS.

BURNER.

1,104,601.

Specification of Letters Patent. Patented July 21, 1914.

Application filed May 5, 1913. Serial No. 765,663.

To all whom it may concern:

Be it known that I, JOHN ZANDER, a citizen of the United States, residing at Chicago, county of Cook, and State of Illinois, 5 have invented certain new and useful Improvements in Burners, of which the following is a specification.

The present invention relates to a burner more particularly adapted to that type of 10 furnaces known as oven or annealing furnaces.

The objects of the present invention are to arrange the burners for the furnace and to construct the conduits for the air and 15 gas so as to conduct the air and gas separately and in an uncommingled state to the interior of the main heating chamber where the combustion takes place.

A further object of the invention is to pre- 20 heat the air of the combustion mixture prior to the time of combustion thereby raising the temperature at the point of combustion a proportion equal to the degree of preheat- ing of the air.

25 A further object of the invention is to utilize the gases passing from the main heating chamber to effect this preheating of the air.

The invention further consists in the fea- 30 tures of construction and combination of parts hereinafter described and claimed.

In the drawings: Figure 1 is a front elevation of an oven provided with the burner of the present invention; Fig. 2 a cross sec- 35 tion on line 2—2 of Fig. 3, looking in the direction of the arrow; Fig. 3 a sectional plan view of the parts shown in Fig. 2; Fig. 4 a section on line 4—4 of Fig. 1 looking in the direction of the arrow; Fig. 5 a cross 40 section through the burner casing taken at the point of communication of the main air and gas supply pipes with said casing; and Fig. 6 a cross section through the burner casing showing the construction of the 45 burner and the relation of the various portions of the burner to the air and gas pass- 50 ages within the casing.

The burner of the present invention, as heretofore stated, is well adapted for use 55 with that type of furnace known as an oven furnace and is used in operations similar to the hardening and annealing of metals, etc. In this type of oven it is of the utmost importance to obtain a high temperature; that is, many of the metals will not be acted upon so as to receive the hardening and annealing

treatment before a temperature of around twenty-four hundred degrees is obtained. It has been difficult in this type of furnace to obtain this degree of heat, and the primary object of the invention is to construct a burner so as to obtain a high temperature without consuming any more gas than is consumed ordinarily.

Referring to the drawings, and particu- 60 larly to Fig. 1, the furnace with which the burner is shown as applied consists of a base 7 of any suitable size and configuration and supported on this base is what may be termed the body portion 8 of the furnace. 70 The body portion is made of any suitable material and is provided with an opening in its front wall intended to be closed by a door 9 operated by suitable means. The interior of the body portion 8 is divided into a main heating chamber 10 of suitable size and a preheating chamber 11, preferably located below the main heating chamber. Communication is established between this main heating chamber and the preheating 75 chamber by means of a passage 12 and a pas- 80 sage 13.

The preheating chamber has located ap- 85 proximately centrally thereof a division wall 14 which as will be seen by referring to Fig. 3, does not extend the entire length of said chamber, but is terminated so as to leave a passage 15 therein. It might be said that this cross wall 14 divides the heating chamber into a compartment 16 and a com- 90 partment 17 which are in communication with one another through the medium of the passage 15. It will be noted that the passage 12 is in communication with the compartment 16 and the passage 13 is in communication with the compartment 17. Located within the compartment 16 is an air pipe 18 which winds back and forth therein and located within the compartment 17 is an air pipe 19 which winds back and 95 forth therein. The pipes 18 and 19 are connected by a suitable union 20 with a main air supply pipe 21, (see Fig. 1), and the pas- 100 sage of air through this main supply pipe may be controlled by means of a suitable valve 22.

Located upon opposite sides of the body portion of the furnace are housings or casings 23, each similar in style and construction, and each of these housings or casings is divided in its interior by means of a se- 110 ries of vertical division walls 24, (see Fig.

4), which extend longitudinally thereof and from end to end thereof and divide the interior of said casings into outer chambers 25 and 26, and an intermediate or center 5 chamber 27, although there are three of these casing chambers or passages shown in the construction illustrated, it is understood that this particular number may be varied, if desired. The outer chambers 26 and 25 10 are intended to receive the supply of gas, and the intermediate chamber 27 is intended to receive the supply of air. The pipes 18 and 19 extend to the outside of the casing and communicate with the chamber 27 as 15 more clearly shown in Figs. 3 and 5. In these figures it will be seen that a flanged plate 28 is affixed to the lower face of the casing through the medium of suitable locking members 29. The end of the air pipes 20 18 and 19 are entered into this flange plate. It is understood there is one of these flange plates for each of the housings 23, and that the plate on one of the housings 23 receives the pipe 18 and the plate on the other housing 25 23 receives the pipe 19.

By referring to Fig. 5 it will be seen that the outer walls of the housings 23 are cut away at the point where the plates 28 are attached thus providing a passage 30 to permit the entrance of air into the channels or 30 passages 27 of the casings 23. Plates 31 similar to the plates 28 are attached to the upper faces of the housings 23, one for each housing, and these plates each receive a gas 35 pipe 32. By referring to Fig. 1 it will be seen that there is one of these gas pipes for each casing 23. By referring to Fig. 5 it will be seen that the upper walls of the casings 23 are cut away where the plates 31 are 40 attached to provide passages 33 so that communication between the gas pipes 32 and the chambers 25 and 26 of the housings are established.

A series of conductors 34 are supported in 45 the cross walls of the housings or casings 23, and each consists of an outer pipe or conductor 35, an intermediate pipe or conductor 36, and an inner pipe or conductor 37. The pipe 37 is in communication with the 50 chamber 26, the pipe 36 is in communication with the chamber 27, and the pipe 35 is in communication with the chamber 25. It will be noticed that each of the pipes is 55 spaced away from each other so that an outer passage 38, an intermediate passage 39, and an inner passage 40 is provided. The passage 38 is in communication with the gas chamber 25 of the casing and serves to conduct gas to the heating chamber, the 60 chamber 39 is in communication with the air passage 27 of the casing and serves to conduct air to the heating chamber, and the passage 40 is in communication with the gas chamber 26 of the casing and also serves to 65 conduct gas to the heating chamber.

The construction comprising the casings 23, division walls 24, passages 25, 26, and 27, together with the conductors 34, constitute what is termed the burner for the furnace.

From the foregoing it will be seen that the air and gas are conducted separately and in an uncommingled state until they finally emerge from the burner and pass into the combustion chamber. The point of combustion is therefore at the outer edge of the burner, and thus no diminution in the efficiency of the heat is brought about by reason of the combustion taking place at a point removed from the main heating chamber. 70

It will be remembered that the air enters the chamber 27 in a preheated condition. Therefore when the combustion takes place the combustion mixture consists of a volume of air already preheated to a certain degree and a volume of gas. It is obvious that under these conditions a greater degree of heat will be given off by the combustion than would be the case if air which was not preheated were used, since in that case the heat necessary to bring the air up to a certain temperature would have to be entirely drawn from the heat of combustion, whereas in the present case the raising of the air to this temperature is accomplished by means of a preheating and a less volume of heat is drawn from the heat of combustion to raise the air to the desired degree. It will also be seen from the foregoing that I use only the gases which are drawn off from the main heating 85 chamber for the purpose of effecting this preheating operation and thus make use of a waste product to increase the efficiency of the combustion. By locating the passages 90 12 and 13 in the manner described, the heat 100 from the main heating chamber is drawn into the compartment 16 at its rear, is sucked through said compartment, thence through the passage 15 and into the compartment 17 where it is joined by the heat 110 coming through the passage 13. Thus we have a travel of heat through the compartments 16 and 17 which is approximately of 115 equal degree; that is, any diminution in the heat coming through the passage 12 which might be caused by reason of its travel through the compartment 16 will be made up by the fresh heat coming from the passage 13, so that the gas which travels through the compartment 17 has approximately the same degree as that traveling through the compartment 16.

A stack 41 of suitable construction is in communication with the compartment 17 at the rear end thereof and this stack provides the requisite outlet to draw off the gases from the compartments 16 and 17 and maintain the circulation of heat through these compartments. By the arrangement previously described the superheated air trav- 125 130 135

eling through the chamber 27 of the casings 23, as well as through the passage 39 will tend to raise the temperature of the gas passing through the chambers 25 and 26 of 5 the casings 23 as well as the passages 38 and 40, so that these gases, when combustion takes place, will also be raised to a temperature higher than would otherwise be the case.

10 I claim:

1. A burner comprising a casing, a plurality of division walls in said casing extending longitudinally thereof and dividing the interior of the casing into separate gas and air 15 passages, plates secured to the upper and lower faces of said casing, an air supply pipe entered into one of said plates, a gas supply pipe entered into the other of said plates, said casing being cut away at the 20 point of attachment of one of said plates and in alinement with the air passage to provide communications between the air pipe and the air passage, and said casing also being cut away at the point of attachment of the other of said plates and in alinement with the gas passage to provide communication between the gas pipe and gas 25 passage, and conductors mounted in the walls of said casing, said conductors estab-

lishing a series of passages at right angles 30 to said casing passages, each conductor passage communicating with a casing passage, substantially as described.

2. A burner comprising a casing, a plurality of division walls in said casing extending longitudinally thereof, and dividing the interior of the casing into a separate air passage and a separate gas passage, means on said casing providing a supplemental chamber, means establishing communication between the supplemental chamber and air passage, a main air supply pipe communicating with the supplemental chamber, a second supplemental chamber on 35 said casing, means establishing communication between the second supplemental chamber and gas passage, a main gas supply pipe communicating with the second supplemental chamber and conductors mounted in the walls of said casing, said conductors 40 establishing a series of passages at right angles to said casing passages, and each conductor passage communicating with a casing passage, substantially as described.
